UNITED STATES PATENT OFFICE.

FRANCIS DE WILLY, OF LOS ANGELES, CALIFORNIA.

TRANSFORMER.

Application filed April 20, 1926. Serial No. 103,378.

My invention relates to high frequency transformers, particularly adapted, although not necessarily, for use in radio apparatus.

It is a purpose of my invention to provide a transformer so wound that its magnetic field is confined to a restricted area so that in use in a radio circuit, for example, where it is necessary to arrange two or more transformers in close proximity to each other, the overlapping of the fields thereof is prevented and the resultant interstage coupling or spray feedback eliminated.

It is also a purpose of my invention to provide a transformer in which restriction of its magnetic field is accomplished by a simple and novel method of winding the secondary and in such manner that counter-magnetic fields are set up which operate to utilize that part of the primary magnetic field which ordinarily leaks beyond the secondary, thus confining the magnetic field within the area defined by the instrument itself.

A further purpose of my invention is the provision of a transformer which possesses extremely low magnetic losses, to maintain the high frequency resistance at a minimum and thus insuring increased selectivity, volume and natural tone quality when incorporated in a radio receiving circuit.

I will describe only one form of transformer embodying my invention, and will point out the novel features thereof in claims.

In the drawings:

Figure 1 is a view showing in perspective one form of transformer embodying my invention;

Figure 2 is a plan view of the transformer shown in Figure 1.

Referring specifically to the drawings, my invention in its present embodiment comprises an inner frame or sleeve 15 disposed centrally within an outer frame 16, the two frames being of tubular form in the present instance and constructed of suitable insulating material. The outer frame 16 is formed at diametrically opposed points with slots 17, which extend inwardly from one end of the frame and terminate in spaced relation to the other end of the frame.

Within the inner frame 15 is arranged a primary winding 18, while associated with the inner and outer frames is a single length of insulated wire constituting the secondary winding of the transformer. This wire, one end of which is indicated at 19, is trained around the outer side of one-half of the outer

frame 16, or, in other words, extends from one slot 17 to the other. From this point the wire is extended inwardly, as indicated at 20, and tangentially of the inner frame 15, whence it is extended around one side of the frame 15, as indicated at 21, so as to encompass substantially one-half of the frame. From this point the wire extends tangentially from the inner frame 15, as indicated at 22, and in a direction opposed to, but substantially parallel with, the stretch 20. In continuing its winding the wire is trained about the outer side of the other half of the outer frame 16, as indicated at 23, so as to extend from one slot 17 to the other, whence it extends inwardly of the outer frame and tangentially of the inner frame, as indicated at 24, and then around the other half of the inner frame 15, as indicated at 25. From this point the wire is extended tangentially from the inner frame, as indicated at 26, thus completing what may be termed one convolution of the winding.

The remainder of the secondary winding is completed by merely repeating the convolutions as just traced to the opposite end of the wire, as indicated at 27. In this manner the secondary is formed into an inner coil, indicated at C in Figure 2, and two outer coils C', the inner coil being in inductive relation to the primary winding and the outer coils in noninductive relation to the primary winding, as will be seen from considering the following operation.

With current supplied to the primary winding 18 there is induced into the coil C a current which flows in the same direction as the current traversing the primary wire, all as indicated by the arrows in Figure 2, and as a result of this current there will be caused to flow in the coils C' a current which is merely a continuation of the current traversing the coil C. By noting the arrows in Figure 2, the course of the current through all of the coils can be readily traced, and it will be particularly noted that although the current in the coil C is flowing in the same direction as the current of the primary winding, the current of the coils C' flows in directions opposed to the current flow in the respective adjacent portions of the primary winding.

By reason of this the coils C' set up magnetic fields which oppose the magnetic field emanating from the primary winding, and because of the encircling positions of the coils C' it will be manifest that the magnetic fields set up thereby will operate to neutralize the

primary magnetic field to prevent the latter from extending beyond the area defined by the instrument. Of course there will be a slight leakage of the magnetic field through the slots 17 of the outer frame 16, but it will be understood that the frame 16 can be so designed as to render these slots relatively narrow and hence bring the coils C' into closer proximity, thereby completely enclosing the primary magnetic field or the magnetic field of the primary.

A transformer constructed in accordance with my invention possesses a high degree of selectivity through the ability to inductively couple the primary winding to only a relatively small portion of the secondary winding, namely, the coil C. The completely closed magnetic field permits the intimate association of the transformer with others in a radio set without the possibility of the magnetic fields of the two transformers overlapping and thus creating spray feedback or interstage coupling. It is to be particularly noted that the coils C and C' are space wound, which greatly reduces the loss of magnetic energy and as a consequence likewise the high frequency resistance to a minimum.

Although I have herein shown and described only one form of transformer embodying my invention, it is to be understood that various changes and modifications may be made therein without departing from the spirit of the invention, and the spirit and scope of the appended claims.

35 I claim:

1. A transformer comprising an inner tubular frame, a primary in the frame, an outer

tubular frame concentric of the inner frame and formed at diametrically opposed points with slots, and a secondary continuously wound to form a main coil on the inner frame encircling the primary and extending through the slots and to the outer side of the outer frame to form other coils exteriorly of the outer frame.

2. A transformer comprising a winding wound continuously to form two outer coils shaped as segments of a circle with the flat sides facing, and an intermediate tubular coil with the intermediate coil located between the flat sides of the other coils.

3. A transformer comprising a primary and a secondary continuously wound to form an inner coil surrounding the primary and two outer coils positioned and co-acting to substantially surround the inner coil, the secondary coils being so wound that current induced in the inner coil will flow in the same direction as the current in the primary, and the current in the outer coils which will flow in directions opposed to the current flow in the respective adjacent portions of the primary.

4. A transformer comprising an inner frame, a primary thereon, an outer frame around the inner frame, having slots therein, and a secondary continuously wound to form a main coil on the inner frame encircling the primary, and outer coils extending through the slots and to and around the outer side of the outer frame to substantially surround the main coil.

FRANCIS DE WILLY.
